CLAIM

I claim the ornamental design for a sleeved garment, as shown and described.

DESCRIPTION

FIG. 1 is a front elevation view of a sleeved garment.

FIG. 2 is a rear elevation view of the sleeved garment illustrated in FIG. 1.

FIG. 3 is a front and top perspective view of the sleeved garment illustrated in FIG. 1; and,

FIG. 4 is a rear and bottom perspective view of the sleeved garment illustrated in FIG. 1.

The broken lines shown in the drawings illustrate portions of the article which form no part of the claimed design.
